UNITED STATES PATENT OFFICE

GRANT E. POLLOCK, OF CLINTON, ILLINOIS.

MILK-CAN-COVER LOCK.

1,317,891.

Specification of Letters Patent of Inventor.

Patented Oct. 7, 1919.

Application filed October 21, 1918. Serial No. 258,958.

To all whom it may concern:

Be it known that I, GRANT E. POLLOCK, a citizen of the United States, residing at Clinton, in the county of De Witt and State 5 of Illinois, have invented new and useful Improvements in Milk-Can-Cover Locks, of which the following is a specification.

This invention relates to milk and cream can covers of that type wherein means 10 is provided upon the cover for permitting animal heat to be discharged from the interior of the can and to allow fresh air to gain access thereto, the invention aiming primarily to provide means of an improved 15 and simple nature for securing the can cover firmly in position upon the neck of the can so that the same cannot be accidentally removed but which will permit of the same being readily applied to or removed from 20 the can.

A still further object of the invention is to provide simple and effective means for securing the protector to the neck of the can, which means is adjustable to fit under 25 can rims of different sizes so as to cover and close the holes in the can neck commonly employed for wiring-on the ordinary shipping lid.

The invention consists of the features of 30 construction, combination and arrangement of parts hereinafter fully described and claimed, reference being had to the accompanying drawing, in which:—

Figure 1 is a side elevation of the upper 35 portion of a milk can, showing the protector cover applied thereto.

Fig. 2 is an enlarged vertical section through the neck of the can and the cover mounted thereon.

Fig. 3 is a bottom plan view of the cover 40 removed from the can.

Fig. 4 is an enlarged vertical section on line 4—4 of Fig. 3.

Fig. 5 is an enlarged vertical section on 45 line 5—5 of Fig. 4.

Referring to the drawing, 1 designates a milk or cream can provided with the usual neck 2 terminating in the upwardly and outwardly inclined rim flange 3, said flange be-

ing provided with the usual diametrically 50 disposed openings 4 for the passage of fastening wires whereby an ordinary shipping lid may be secured to close the can. The protector embodying my invention is adapted to fit upon and close the rim flange 3. 55 This protector comprises a substantially concavo-convex cover 5 adapted to fit down over upon the flange 3 and of greater diameter than said flange to project peripherally beyond the same. At diametrically 60 opposite sides of this cover 5 are spring metal bracket pieces 6 having downwardly bent outer ends 7. The said downwardly bent outer ends 7 project below the beaded edge of the cover 5 and extend at an angle 65 of inclination corresponding substantially to the angle of inclination of the rim flange 3. Formed in the angular end 7 are threaded openings receiving adjusting and clamping screws 8 carrying at their inner 70 ends clamping heads 9 to bear upon the outer surface of the rim flange 3 and securely clamp the cover 5 thereto. The screws 8 are swiveled at their inner ends to the heads 9, as indicated at 10, and said 75 heads 9 are preferably in the form of disks segmentally cut away at one point to provide a straight transverse bearing edge 11. The bearing edges 11 are adapted to rest against the underside of the cover 5 to hold 80 the disks from rotation, while the inner flat faces of said disks are adapted to bear against the flange 3 for an effective clamping action. The disks 9 are eccentrically mounted on the swiveled ends 10 of the 85 screws 8, such swiveled ends of the screws being arranged at a point closer to the edge 10 than to the diametrically opposite curved edge of the disk. By this construction the disks 9 may be arranged to bear snugly 90 against the cover 5, while they will be provided with portions of maximum depth below the swivels 10 to close the openings 4 when the protector is applied to the can. Hence provision is made for closing the 95 openings 4 of cans having rim flanges 3 of different depths, and in which the openings 4 are arranged at different distances from

the upper edges thereof, the closure of said openings preventing the entrance of dust or dirt to the interior of the can while the protector is applied.

5 The body portion of the cover 5 is provided with a centrally located aperture 12 and a guide flange 13 extending upwardly from and forming a continuation of said aperture. Extending through the aperture 10 and guide flange is a ventilator 14, comprising a tube or cylinder provided throughout its entire depth with perforations, adapted to permit of the discharge of the warm air containing the animal heat from the milk 15 while of sufficiently small size to exclude rodents and all ordinary insect life. The cylinder 14 has a range of adjustment substantially coincident with its length or depth to expose any desired portion of its 20 perforated area to regulate or control the discharge of the animal heat as required or found desirable under different conditions of service, said cylinder being retained in adjusted position by frictional engagement 25 with the flange 13.

The tube or cylinder 14 is closed at its upper end by a concavo-convex cap 15, said cap being of greater diameter than said tube and the flange 13 so as to constitute an umbrella-like shield or canopy which will prevent the dripping or leakage of water into the can through the perforated tube 14 or opening 12. The said cap is of such diameter as to project peripherally well beyond the flange 30 13 so as to shed any water dripping thereon at such a distance beyond the opening 12 as to obviate any liability of the water running toward said opening. It will be understood that the flange 13 acts in this connection as an upstanding curb, which will project to a sufficient height to prevent any water falling upon the cover 5 from splashing upward and entering the opening 12. Hence while the animal heat from the milk 40 or cream will be permitted to freely pass outwardly through the tube or cylinder 14, and cold air to enter to a degree dependent upon the adjustment of said tube or cylinder, it will be evident that at the same time the 45 entrance of water, rodents and insects will be effectually prevented, thus keeping the contents of the can in a thoroughly sanitary condition while being cooled and ventilated. It is a well known fact that an enormous 50 amount of milk and cream is wasted because it is frequently necessary to throw away the milk or cream on account of the impurities entering the same while the animal heat is being extracted therefrom. My invention 55 effectually overcomes this objection and hence effects a saving of the milk and cream ordinarily wasted for the reason stated.

In practice the bracket pieces 6 are preferably made of spring metal so that their

angularly bent ends 7, in addition to adjustably supporting the screws 8, will exert spring pressure upon the disks 9 to hold the same firmly in clamping position, thus obviating any liability of the same being jarred out of place or of the screws becoming loosened from any cause.

It is to be understood that in the use of the invention the protector is applied to the can while the milk or cream is being stored for the extraction of the animal heat therefrom, 75 and that the construction described permits of the ready application of the device and its subsequent removal for the application of the lid or cover employed to seal the can for shipping or other purposes.

The protector is provided with a suitable handle 16 applied to the cap 15 to permit adjustment of the ventilating tube and cap, and to permit the device as a whole to be conveniently manipulated and transported.

Having thus fully described my invention, I claim:

1. In a cover for milk or cream cans, resilient bracket members carried by the cover and having angularly bent ends depending from the edges thereof, adjusting screws threaded in said angularly bent members, and clamping disks swiveled upon the inner ends of said screws.

2. In a cover for milk or cream cans, bracket pieces having downturned ends secured to the cover at diametrically opposite sides thereof, screws adjustably mounted in the downturned ends of said bracket pieces, and disks eccentrically swiveled upon said screws, the said disks having straight clamping edges at one side thereof arranged closer to the eccentric pivot than the diametrically opposite edges of the disks.

3. In a cover for milk or cream cans, the combination of a can having a neck portion, a cover of greater diameter than said neck portion and formed to rest upon the rim edge thereof, downwardly projecting resilient members upon the said cover at the outer edges thereof, screw members extending through said downwardly projecting members, and plates swiveled to the inner ends of said screw members and adapted to engage with the said neck portion of the can.

4. In combination, a can having openings in its sides, a cover for said can, clamping members carried by said cover and movable toward or away from the can sides, and disks to be held in engagement with the can sides over said openings by said clamping members.

5. In combination, a can having openings in its sides, a cover for said can, brackets at the edges of said cover, screw members threaded in said brackets and movable toward or away from said can sides, and disks

swiveled to said screw members and adapted to engage the can sides and to close said openings.

6. In combination, a can having openings 5 in its sides, a cover for said can, resilient L-shaped brackets at the edges of said cover and depending from the latter, screw members threaded in said brackets and movable

toward or away from the axis of the cover, disks swiveled on the inner ends of said 10 member to cover said openings, and the said disks being cut away at one side so as to snugly engage with the underface of said member.

In testimony whereof I affix my signature. 15
GRANT E. POLLOCK.
